ROTATING COMBUSTION PRODUCTS GENERATOR WITH TURBULENT FUEL INJECTION ZONE

Paul Kollsman, New York, N. Y.

Application August 24, 1945, Serial No. 612,389

6 Claims. (Cl. 60—41)

1

This invention relates to a thermodynamic engine in which there is a continuous flow of the energy producing gas.

An object of the invention is the provision of a thermodynamic engine of high efficiency in which a gas is compressed, heated and expelled in a single rotating unit.

Another object of the invention is the provision of a thermodynamic engine in which compression and heating of a gas is effected in a rotating member without travel through stationary passages.

Another object of the invention is provision of a thermodynamic engine having a self-rotating combined compressor and heating member.

Another object of the invention is a thermodynamic engine in which a gas enters a rotating member adjacent to the axis thereof, is compressed at the periphery by the action of centrifugal force upon the gas column and again expelled adjacent to the axis of the rotary member, with heat energy supplied to the gas in its compressed state adjacent to the periphery of the rotary member, with rotation of the rotary member secured by the reaction of the gas discharge, flow of gas from the member being maintained by the difference in density in the opposite radial paths.

Other objects and features of the invention will be readily apparent to those skilled in the art from the specification and appended drawings illustrating certain preferred embodiments in which:

Figure 1 is a view partly in vertical section of the engine according to the present invention with the rotor shown in elevation.

Figure 2 is an enlarged vertical sectional view of the engine with the collector and nozzle broken away, the view being taken on line II—II of Fig. 1.

Figure 3 is a partial front elevational view, partly in section and with the case broken away to show the internal rotor.

Figure 4 is a vertical sectional view similar to Figure 2 but showing a modified form of the invention.

Figure 5 is a partial detail view of a modified form of intake for the engine.

In the form of the invention shown in Figures 1, 2, and 3, there are shown a pair of casing sections 1 and 2 which combine to form an enlarged cylindrical chamber 3. Casing section 1 has an axial extension 4 forming an intake duct, while casing section 2 has an axial extension 5 forming a collecting chamber 6 and a nozzle portion 7.

2

Within the duct 4 upon spider legs 8 is mounted a support 9 for a stationary shaft 11. Upon the shaft 11 by bearings 12 and 13 is mounted a rotor 14 formed of two half sections 15 and 16, joined together in spaced relation by pins 17 so as to form an insulating air space between the sections. Adjacent to the axis of the rotor 14 the space between the sections is filled by an insulating ring 18.

10 Upon the rotor sections 15 and 16 are mounted aligned fins 19 and 21, serving to divide the space within chamber 3 into a plurality of individual chambers as shown more particularly in Figures 1 and 3. As shown in Figures 1 and 2, these chambers are of generally U shape with spaced radial legs and a connecting transverse bight. At the intake portion of the engine the fins 19 have portions 22 which extend generally axially of the engine and have their ends curved in the direction of rotation of the rotor to form scoops to pick up and direct the incoming gas into the chambers between the rotor fins. The fins 21 on the exit side of the engine are provided with portions 23 which extend generally axially of the rotor and have their ends curved away from the direction of rotation to serve as discharge nozzles.

Spaced about the periphery of the casing section 1 are a plurality of fuel injection nozzles 24 and ignitor plugs 25. Upon the stationary shaft 11 is mounted a stator 26 of an electric motor, the rotor 27 of which is mounted upon section 15 of rotor 14. The wiring for the motor indicated at 28 leads through one of the spider legs 8 through support 9 and shaft 11 to the motor stator 26.

35 In the operation of the engine according to this invention the rotor 14 is initially rotated by the electric motor formed by the stator 26 and rotor 27 until it has been brought up to considerable speed. Thereafter fuel is injected into chamber 3 from the nozzles 24 and is ignited by the plugs 25. Thereafter the electric motor and the ignitor plugs may be de-energized, as combustion will thereafter be continuous and the rotor 14 self-driving.

40 The rotor 14 will operate at relatively high speeds at which the gas adjacent the periphery of the chamber 3 will be in a compressed state due to the action of centrifugal force upon the gas columns in the chamber legs between fins 19 and 21. Due to the heating of the gas effected in the combustion chambers within chamber 3, the gas in the leg between fins 21 will be at a much higher temperature than the gas in the leg between fins 19 and thus at a much lower density.

The difference in weight of the two columns of gas in the two legs produces an axial flow of gas from the intake duct into the chambers between fins 19, radially to the periphery of chamber 3, then transversely across the bight of the U-shaped passage, again radially through the chambers formed between the fins 21 and through the discharge nozzle between the portions 23 of fins 21 into the collector chamber 6.

As the gases pass from the periphery of chamber 3 to the nozzle portions 23, they return to the rotor 14 the major portion of their rotational energy, since they are moving in a direction of decreasing radius of rotation. Accordingly rotational energy which was transmitted to the incoming gas passing between fins 19 in a direction of increasing radius is substantially returned to the machine.

The portions 23 of fins 21 form discharge nozzles in a direction having a substantial tangential component and the reaction to the discharge serves to drive the rotor 14. The scoop portions 22 of fins 19 assist the normal axial flow in picking up and directing the incoming air or gas into the chambers between the fins 19. The gases discharging from the nozzles formed between the portions 23 of the fins 21 are collected within chamber 6 and are discharged through the nozzle 7 in a continuous jet to secure an axial thrust, serving as a working force for the engine.

Of course it will be understood that, as in any rotating machinery, the working energy of the engine may be taken direct from the rotor 14 in conventional manner, in combination with or without utilizing the reactive jet force.

While direct fuel injection and ignition has been specifically illustrated in the drawing, it will be understood that the engine according to the invention will function with any means for introducing heat energy into the gas adjacent to the bight of the U-shaped gas path. When direct fuel injection is used, it is preferable to introduce the fuel immediately in advance of the end of the entrance leg of the U-shaped path, so as to insure more complete combustion of the fuel within the chamber 3.

In the modification of the invention shown in Figure 4, provision is made for the internal injection and ignition of the fuel and there is provided a floating casing about the rotor 14 to reduce the frictional loss occurring at the contact of the rotating air columns with the stationary casing. Like parts in Figure 4 have been given the same reference numerals as Figure 2. The fuel injection nozzle 24 and ignitor plugs 25 are now omitted and fuel injection is secured through the tube 31 extending through the spider leg 8, stationary support 9 and stationary shaft 11 to a discharge passage 32 leading from the shaft 11. Fuel sprayed through the passage 32 is collected within a circumferential groove 33 and a plurality of radial passage ways 36 extend toward the periphery of the rotor section 35 and terminate in discharge nozzles 37 from which the fuel is sprayed into the chambers between fins 19.

The winding of the rotor 27 of the electric starting motor is connected to a spark coil 38 from which ignition wires 39 lead radially to ignitor plugs 41 adjacent the fuel discharge nozzles 37.

The casing sections 1 and 2, Figure 4, are made larger than those of Figure 2 to accommodate between the fins 19 and 21 and the interior walls of the casing sections an intermediate floating

4
casing 42 having only mechanical clearance with respect to the fins and the interior surfaces of the exterior casing. The casing 42 is free to rotate on bearings 43, of any desired type, as a follower to the rotation of the rotor 14. The casing 42 has been shown as a continuous piece of metal with the understanding that it can be soldered or welded in place about the rotor or may be joined in any desired manner. With the introduction of the casing 42 the frictional resistance of the rotating gases with respect to the outer casing is greatly reduced so that the efficiency of the engine is increased. The operation of the engine of Figure 4 is identical with that described for the engines 1, 2, and 3, the fuel now being supplied internally and the casing 42 following the rotation of the rotor 14 at fractional speed by frictional engagement with the rotary gases to reduce the frictional loss at the casing wall.

In the modification of the invention of Figure 5, for the spider legs 8 there have been substituted a plurality of directional vanes 45 which not only maintain the support 9 mechanically but serve to direct the incoming gas into a rotary path. In this modification the scoop portions 22 are omitted and the rotor fins on the incoming side, indicated at 46, have straight ends since the incoming air or gas will be moving at substantially the same tangential velocity as the entrance ends of the fins due to the directional vanes 45 through which the air is drawn by the axial flow.

While the drawings illustrate the bights of the U-shaped chambers as being relatively short, it will be understood that they may have a considerable axial extension to secure more complete combustion of the fuel while the air is at maximum compression. Also while the legs of the chambers extending from the axis toward the periphery have been illustrated and referred to as radial, it will be understood that any directional path having a radial component may be used for these legs.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. A combustion products generator comprising a stationary casing having an interior wall defining a rotor chamber, a rotor mounted for rotation within said chamber, said rotor including a body and a plurality of circumferentially spaced substantially radially extending blades on said body, said blades together with said body forming a plurality of substantially U-shaped rotor channels which together with the unbroken interior wall of the casing constitute individual and separate U-shaped passages, the legs of the U extending substantially radially, the bight of the U lying remote from the rotor axis, one leg constituting a compression passage and its end constituting an intake adjacent the rotor axis, the other leg constituting an expansion passage, and its end constituting an outlet adjacent the rotor axis, the outlet being directed at an angle to impart a tangential component to the direction of discharge of the combustion products tending to spin the rotor by reaction force, means in the casing wall for injecting fuel into the rotor channels adjacent the bight, whereby the

fuel is intimately mixed with the compressed gas flowing through the channels by reason of the turbulence of the gas due to the relative movement of the channels with respect to the casing, and means for igniting the resulting combustible mixture.

2. A combustion products generator comprising a stationary casing, a rotor mounted for rotation within said casing, said rotor including a body and a plurality of circumferentially spaced substantially radially extending blades on said body, said blades together with said body forming a plurality of substantially U-shaped rotor channels which together with the unbroken interior wall of the casing constitute individual U-shaped passages, the legs of the U extending substantially radially and the bight of the U lying remote from the rotor axis, one leg constituting a compression passage and its end constituting an intake, the other leg constituting an expansion passage, and its end constituting an outlet, said body comprising two body portions, one body portion including said first leg and the other body portion including the second leg of the U-channel, the first body portion being separated from the second body portion by a zone of reduced heat conductivity to retard the transfer of heat from one body portion to the other, means for injecting fuel into the rotor channels adjacent the bight, whereby the fuel is evenly distributed over the several channels and intimately mixed with the compressed gas flowing through the channels by reason of turbulence of the gas due to the relative movement of the channels with respect to the casing and the fuel injecting means, and means for igniting the resulting combustible fuel mixture.

3. A combustion products generator comprising a casing having an interior wall defining a rotor chamber, a rotor mounted for rotation within said chamber, said rotor including a body and a plurality of circumferentially spaced substantially radially extending blades on said body, said blades together with said body forming a plurality of substantially U-shaped rotor channels which together with the unbroken interior wall of the casing constitute individual and separate U-shaped passages, the legs of the U extending substantially radially and the bight of the U lying remote from the rotor axis, one leg constituting a compression passage and its end constituting an intake adjacent the rotor axis, the other leg constituting an expansion passage, and its end constituting an outlet adjacent the rotor axis, said blades constituting continuous channel walls within the leg portion and the bight portion of said passages, means on said rotor for injecting fuel into the individual rotor channels adjacent the bight, whereby the fuel is intimately mixed with the compressed gas flowing through the channels by reason of turbulence of the gas due to relative movement of the channels with respect to the casing, and means on said rotor for igniting the combustible fuel mixture.

4. A combustion products generator comprising a casing, a rotor within said casing, a freely rotatable shell between the rotor and the interior surface of the casing, said shell having an unbroken peripheral wall, said rotor including a body and a plurality of circumferentially spaced substantially radially extending blades on said body, said blades together with said body forming a plurality of substantially U-shaped rotor channels which together with the interior

wall of said shell constitute individual and separate U-shaped passages, the bight of the U lying remote from the rotor axis, one leg of the U constituting a compression passage and its end constituting an intake adjacent the rotor axis, the other leg constituting an expansion passage, and its end constituting an outlet adjacent the rotor axis, said blades constituting continuous channel walls within the leg portion and the bight portion of said passages, means on said rotor for injecting fuel into the individual rotor channels adjacent the bight, whereby the fuel is intimately mixed with the compressed gas flowing through the channels by reason of turbulence of the gas due to the relative movement of the channels with respect to the shell, the shell spinning at a lower rate than the rotor, and means on said rotor for igniting the combustible fuel mixture.

5. A combustion products generator comprising a casing having an interior wall defining a rotor chamber, a rotor within said chamber, said rotor including a body and a plurality of circumferentially spaced substantially radially extending blades on said body, said blades together with said body forming a plurality of substantially U-shaped rotor channels which together with the unbroken interior wall of the casing constitute individual and separate U-shaped passages, the legs of the U extending substantially radially and the bight of the U lying remote from the rotor axis, one leg constituting a compression passage and its end constituting an intake, the other leg constituting an expansion passage, and its end constituting an outlet, said blades constituting continuous channel walls within the leg portion and the bight portion of said passages, means for providing internal combustion within the rotor channels including means for injecting fuel into the individual rotor channels adjacent the bight, the injected fuel being intimately mixed with the compressed gas flowing through the channels by reason of the turbulence of the gas set up by the relative movement of the channels with respect to the interior wall of the casing.

6. A combustion products generator comprising a casing having an interior wall defining a rotor chamber, a rotor within said chamber, said rotor including a body and a plurality of circumferentially spaced substantially radially extending blades on said body, said blades together with said body forming a plurality of substantially U-shaped rotor channels which together with the unbroken interior wall of the casing constitute individual and separate U-shaped passages, the legs of the U extending substantially radially and the bight of the U lying remote from the rotor axis, one leg constituting a compression passage and its end constituting an intake, the other leg constituting an expansion passage, and its end constituting an outlet, the rotor body comprising two body portions, one body portion including said first leg and the other body portion including the second leg of the U-channel, the first body portion being separated from the second body portion by a zone of reduced heat conductivity to retard the transfer of heat from one body portion to the other, means for providing internal combustion within the rotor channels including means for injecting fuel into the individual rotor channels adjacent the bight, the injected fuel being intimately mixed with the compressed gas flowing through the channels by reason of the turbulence

of the gas set up in each channel by the relative movement of the channels with respect to the interior wall of the casing.
